UNITED STATES PATENT OFFICE.

LAWRENCE LEE SCHAUER, OF CINCINNATI, OHIO, ASSIGNOR TO THE CINCINNATI BICKFORD TOOL COMPANY, OF CINCINNATI, OHIO, A CORPORATION OF OHIO.

CONTINUOUS STRAP FOR GUARDING DRILL SHAFTS.

Application filed February 10, 1925. Serial No. 8,187.

To all whom it may concern:

Be it known that I, LAWRENCE LEE SCHAUER, a citizen of the United States, and residing at Cincinnati, in the county of Hamilton and State of Ohio, have invented new and Improved Continuous Straps for Guarding Drill Shafts, of which the following specification is a full disclosure.

This invention deals with the covering of the rotating shafts on a drilling machine to protect the operator of the machine against injury and concerns chiefly the enclosing of the rotating shafts on a radial drilling machine.

15 In a radial drilling machine, the drill head, which is carried by and movable along the radial arm, is connected through a slot in the arm to an arm shaft located within the arm. The slot in the radial arm serves to take care of the connecting means between the drill head and the arm shaft during the movement of the head along the arm. One feature of my invention is to maintain the slot in the arm covered during the movement of the drill head.

The radial arm of the drill is movable in a vertical direction and during the vertical movement of the arm, the arm shaft is maintained in operative connection with a vertical driving shaft. The vertical driving shaft is left completely exposed in many cases which is undesirable from the standpoint of safety to the operator of the machine. Another feature of my invention is to maintain the vertical driving shaft completely enclosed during the operation of the drilling machine and irrespective of the vertical movement of the radial arm.

Preferably, in a radial drilling machine constructed in accordance with my invention, a vertical driving shaft is enclosed in a casing mounted on the member which supports the radial arm. It is necessary, however, to form a vertical slot in the casing to take care of the connection between the arm shaft and the vertical driving shaft during the vertical movement of the radial arm. The slot thus formed in the casing leaves the vertical drive shaft unenclosed on one side thereof. My invention includes provision for covering the slot in the casing and also for covering the slot in the radial arm by a single flexible strip. The strip is secured to opposite ends of the slot in the casing and extends under rollers on the

radial arm and over rollers on the drill head in such manner as to completely cover the two slots. The two slots are maintained covered irrespective of the vertical movement of the radial arm and irrespective of the movement of the tool head along the arm. Preferably the flexible strip is connected to the casing at one end of the casing slot by means of a spring member so as to maintain a strip taut under all working conditions.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

In the accompanying drawing, Figure 1 is an elevational view of a radial drilling machine having the shafts thereof protected in accordance with my invention. Fig. 2 is an end view of the radial arm shown in Fig. 1 of the drawing. Fig. 3 is a sectional view taken along line 3—3 of Fig. 1.

Referring to the drawing, a sleeve member 1, which is mounted on a post or column 2, supports a radial arm 3. The sleeve member is rotatable on the post 2 in the customary manner and the arm 3 is vertically adjustable on the sleeve member 1. A tool head 4, which carries a suitable drilling tool (not shown), is supported by and movable on the radial arm 3. The tool head 4 is connected to an arm shaft 5 by means of a shaft 6 and bevelled gear wheels 7. The arm shaft 5 is located within the radial arm 3 and is operated by means of a vertical driving shaft 6. The shaft 6, which connects the tool head 4 with the arm shaft 5, extends through a slot 8 which is formed in the top side of the arm. The slot 8 serves to take care of the shaft 6 during the movement of the head along the arm. One of the main features of my invention is to maintain the slot on the top of the radial arm covered at all times during the operation of the machine.

The arm shaft 5 carries a bevelled gear wheel 11 which meshes with a bevelled gear 12 which is splined to the vertical driving shaft 6. The bevelled gear wheel 12 is carried by a bracket 13 which projects from the end of the radial arm 3, as shown in Fig. 1 of the drawing. Preferably a casing 14, which is supported between brackets 15 and 16 on the sleeve member 1, is provided for enclosing the vertical driving shaft 6. However, it is necessary to form a slot 17 in the casing 14 in order to take care of the connection between the arm shaft 5 and the vertical driving shaft 6 during the vertical movement of the radial arm. The slot 17 formed in the casing 14 leaves the vertical driving shaft 6 exposed on one side thereof.

The vertical driving shaft 6 is operated by suitable gearing 19 located in the top of the sleeve member 1, as shown in Fig. 1 of the drawing. The gearing 19 also serves to operate a shaft 20 for controlling the vertical movement of the radial arm 3 on the sleeve member. Suitable means may be provided for operating the gearing 19 by means of a main driving shaft 19^a which is located within the post or column 2. Inasmuch as my invention is not particularly related to the specific driving means for the radial drill a further description thereof is deemed unnecessary.

A flexible strip 24, which may be composed of metal or fabric or any other suitable material is provided for covering the slot 17 in the casing 14 and for covering the slot 8 in the radial arm 3. One end of the flexible strip 24 is secured to the bracket 15 near the upper end of the slot 17 in the casing 14. The strip extends from the upper end of the slot along the casing and around a roller 25 on the end of the arm 3 adjacent to the casing. Such portion of the strip serves to cover the upper end of the slot 17. The strip 24 extends along the slot 8 in the arm 3 to a roller 26 which is mounted on the drill head 4. In order to cover the slot 8 on the other side of the head 4, the strip 24 is carried over two rollers 27 and 28 located at the top of the head 4 and under a roller 29 which is located on the lower part of the head adjacent to the slot. From the roller 29, the strip 24 is carried along the slot 8 to rollers 30 and 31 which are located at the end of the radial arm 3. After passing over the two rollers 30 and 31 the strip 24 extends under a roller 32 on the end of the arm adjacent to the casing 14 and then along the slot 17 to the bracket 16.

A spring member 33 is provided between the end of the strip 24 and the bracket 16 in order to exert a force tending at all times to maintain the strip 24 taut. It is to be understood, however, that any other suitable means may be provided for exerting a force tending to maintain the strip taut.

During the vertical movement of the arm 3 on the sleeve 1, the rollers 25 and 32 on the arm serve to hold the strip 24 in position over the slot 17. Thus irrespective of the movement of the radial arm, the strip 24 covers any part of the slot which otherwise would be exposed. The rollers 26 and 29, which are carried by the tool head 4, hold the strip 24 in position over the slot 8 during the movement of the head along the arm irrespective of the position of the head and of the movement of the head along the arm 3. The rollers 26 and 29 hold the strip 24 in position to cover the parts of the slot 8 which otherwise would be exposed. Thus it is apparent a single flexible strip is provided for covering the slot in the casing and the slot in the radial arm irrespective of the movement of the head and irrespective of the movement of the radial arm. Although the strip 24 is shown connected to the brackets 15 and 16, which support the casing 14, it is to be understood that the ends of the strip may be connected directly to the casing 14 if so desired.

Without further analysis, the foregoing will so fully reveal the gist of this invention that others can by applying current knowledge, readily adapt it for various utilizations by retaining one or more of the features that, from the standpoint of the prior art, fairly constitute essential characteristics of either the generic or specific aspects of this invention and, therefor, such adaptations should be, and are intended to be, comprehended within the meaning and range of equivalency of the following claims:

Having thus revealed this invention, I claim as new and desire to secure the following combinations and elements, or equivalents thereof, by Letters Patent of the United States:

1. In a machine tool, the combination comprising an elongated member having a slot formed therein; a sliding mechanism movable along the elongated member and projecting through the slot into the elongated member; and means comprising a flexible strip connected to the elongated member at each end of the slot therein and arranged to cover such slot on each side of the mechanism irrespective of the movement of the sliding mechanism along the elongated member.

2. In a machine tool, the combination comprising an elongated member having a slot formed therein; a sliding mechanism movable along the elongated member and projecting through the slot into the elongated member; means comprising a flexible strip connected to the elongated member at each end of the slot therein and arranged to extend around said sliding mechanism and to cover such slot on each side of the sliding mechanism irrespective of the movement of

the sliding mechanism along the elongated member; and resilient means so connected to one end of the flexible strip as to maintain it taut.

5 3. In a machine tool, the combination comprising an elongated member having a slot formed therein; mechanism comprising an arm movable along the elongated member and projecting through said slot into 10 the member, said arm having a slot formed therein transverse to the slot in said elongated member; an operating member movable along the arm and projecting through the arm slot into the arm; a flexible strip 15 connected to said elongated member at each end of the slot therein and having its intermediate portion extending about said arm lengthwise thereof; guides adapted to hold said strip adjacent the slot in said elongated member; and means to hold said strip continuously in proximity to the slot in the arm at opposite sides of said operating member as said member is moved along said arm.

25 4. In a machine tool, the combination comprising an elongated member having a slot formed therein; mechanism comprising an arm movable along the elongated member and projecting through said slot into 30 the member, said arm having a slot formed therein transverse to the slot in said elongated member; an operating member movable along the arm and projecting through the arm slot into the arm; a flexible strip 35 connected to said elongated member at each end of the slot therein and having its intermediate portion extending about said arm lengthwise thereof; guides adapted to hold said strip adjacent the slot in said elongated member; means to hold said strip continuously in proximity to the slot in the arm at opposite sides of said operating member as said member is moved along said arm; and resilient means acting upon the flexible strip for maintaining it taut.

5. In a machine tool, the combination comprising an elongated member having a slot formed therein; mechanism comprising an arm movable along the elongated member and projecting through the slot into the member, said arm having a slot formed therein; an operating member movable along the arm and projecting through the slot into the arm; and means comprising a flexible strip for covering the slot on each side of the arm and for covering the arm slot on each side of the operating member irrespective of the movement of the arm or of the movement of the operating member.

60 6. In a machine tool, the combination comprising an elongated member having a longitudinal slot formed therein; a rotating shaft mounted in said elongated member; a sliding member movable along the elongated member; a shaft mounted in said

sliding member and connected to said rotating shaft, the shaft in said sliding member projecting thru the slot in said elongated member; and a single flexible strip extending along the slot and around the 70 sliding member for covering the slot on each side of the sliding member irrespective of the movement of the sliding member.

7. In a machine tool, the combination comprising an elongated member having a 75 longitudinal slot formed therein; a rotating shaft mounted in said elongated member; a sliding member movable along the elongated member; a shaft mounted in said sliding member and connected to said rotating shaft, the shaft in said sliding member projecting through the slot in said elongated member; a single flexible strip extending along the slot and around the sliding member for covering the slot on each 80 side of the sliding member irrespective of the movement of the sliding member; and resilient means for maintaining the strip taut.

8. In a radial drilling machine, the combination comprising a radial arm; a tool head mounted to have sliding movement on the radial arm; an arm shaft mounted in said arm; means comprising a shaft mounted on the head and projecting 90 through a slot in the arm for connecting the head to the arm shaft; and a flexible strip extending along the slot on each side of the head and around the head to cover the slot irrespective of the movement of the 95 head along the arm.

9. In a radial drilling machine, the combination comprising a radial arm; a tool head mounted to have sliding movement on the radial arm; an arm shaft mounted in 100 said arm; means comprising a shaft mounted on the head and projecting through a slot in the arm for connecting the head to the arm shaft, a flexible strip connected at its opposite ends to the drilling machine and extending along the slot on each side of the head and around the head to cover the slot irrespective of the movement of the head along the arm; and a resilient member connected to the strip for 105 maintaining it taut.

10. In a radial drilling machine, the combination comprising a rotatable sleeve; a radial arm mounted to have sliding movement on said sleeve; a tool head mounted to have sliding movement on said arm; a vertical driving shaft mounted on said sleeve; an arm shaft mounted on said arm and connected to said vertical driving shaft; a casing surrounding said vertical shaft 115 and having a slot formed therein, said slot taking care of the arm connection to the vertical shaft during the vertical movement of the arm; a slot formed in the arm to permit a connection between the head and 120

the arm shaft; a single flexible strip having its ends secured to said casing at opposite ends of the slot therein and its intermediate portion extending about said arm lengthwise thereof, and means to hold said strip against transverse faces of said casing and arm for covering the slot on both sides of the arm and for covering the slot on both sides of the tool head irrespective of the movement of the arm and of the tool head.

11. In a radial drilling machine, the combination comprising a rotatable sleeve; a radial arm mounted to have sliding movement on said sleeve; a tool head mounted to have sliding movement on said arm; a vertical driving shaft mounted on said sleeve; an arm shaft mounted on said arm and connected to said vertical driving shaft; a casing surrounding said vertical shaft and having a slot formed therein, said slot taking care of the arm connection to the vertical shaft during the vertical movement of the arm; a slot formed in the arm to permit a connection between the head and the arm shaft; a single flexible strip connected to said casing at opposite ends of the slot in the casing and extending along that portion of the slot in the casing above said arm; guides directing the strip lengthwise of the arm over the slot therein, around the tool head and back to said casing beneath said arm; and means to hold the strip over that portion of the slot in the casing beneath the arm.

12. In a radial drilling machine, the combination comprising a rotatable sleeve; a radial arm mounted to have sliding movement on said sleeve; a tool head mounted to have sliding movement on said arm; a vertical driving shaft mounted on said sleeve; an arm shaft mounted on said arm and connected to said vertical driving shaft; a casing surrounding said vertical shaft and having a slot formed therein, said slot taking care of the arm connection to the vertical shaft during the vertical movement of the arm; a slot formed in the arm to permit a connection between the head and the arm shaft; a single flexible strip connected at one end of the casing slot and extending along the slot in the casing and in the arm and around the tool head and the arm to the other end of the casing slot for covering the two slots irrespective of the movement of the arm and of the tool head; and a resilient member connected to one end of the strip for maintaining it taut.

13. In a radial drill, in combination, a radial arm providing a housing having a slot

through a wall thereof; a tool head slidably mounted on the radial arm; a shaft journaled lengthwise of said arm within said housing; operating mechanism extending through said slot and slidably connected with said shaft; a single flexible guard extending lengthwise of said arm and adapted to cover said slot at opposite sides of said tool head; means at opposite ends of said arm to maintain said flexible guard in proximity to said slot; rollers located at opposite sides of said tool head and acting upon said guard to maintain it in proximity to said slot adjacent the tool head; and means to guide said guard around said tool head from one of said rollers to the other.

14. In a radial drill, in combination, a sleeve; a radial arm carried by said sleeve and providing a housing having a slot through one wall thereof, a drill-head translatablely mounted on the radial arm and having a portion overlying said slot; a shaft journaled lengthwise of said arm within said housing; means connected with said arm shaft and extending through said slot to transmit power from said shaft into said drill-head; a flexible guard extending lengthwise of said arm; guide members at opposite ends of said slot to hold said guard in proximity to said slot; and means carried by said drill-head to deflect said guard member around said drill-head to permit said drill-head to be shifted relatively to said guard and to maintain the guard in proximity to the slot immediately adjacent opposite sides of said drill-head.

15. A radial drill combining a column; an arm extending radially from said column and provided with a casing having a slot in one wall thereof; a drill head translatablely mounted on the arm and having a portion overlying said slot; a shaft journaled lengthwise of said arm within said casing; means slidably connected with said arm shaft and extending through said slot to transmit power from said shaft into said drill-head; a flexible guard having a portion extending lengthwise of said arm to close said slot; guide means adjacent opposite ends of said arm to hold said guard in proximity to said slot; means carried by said drill-head to hold said guard in proximity to said slot at opposite sides of said drill-head; means to guide the guard around said drill-head; and means for maintaining said guard taut along said arm and around said drill-head.

In witness whereof, I have hereunto subscribed my name.

LAWRENCE LEE SCHAUER.
